H. HURTER

CANE CRUSHING APPARATUS

Filed April 20, 1923

UNITED STATES PATENT OFFICE.

HENRY HURTER, OF ST. LOUIS, MISSOURI, ASSIGNOR TO FULTON IRON WORKS COMPANY, OF ST. LOUIS, MISSOURI, A CORPORATION OF DELAWARE.

CANE-CRUSHING APPARATUS.

Application filed April 20, 1923. Serial No. 383,350.

To all whom it may concern:

Be it known that I, HENRY HURTER, a citizen of the United States of America, and a resident of the city of St. Louis, in the State 5 of Missouri, have invented certain new and useful Improvements in Cane-Crushing Apparatus, of which the following is a full, clear, and exact description, reference being had to the accompanying drawings, forming 10 a part of this specification.

This invention relates generally to improvements in cane crushing apparatus and particularly to a cane crushing apparatus which is provided with means whereby the 15 capacity of said apparatus is increased to the maximum.

A cane crushing apparatus of the type disclosed in the present application is a very large structure capable of crushing more 20 than a thousand tons of cane per day and, of course, an enormous structure such as this would be extremely expensive. The most important consideration in connection with 25 an expensive apparatus of the sort mentioned, is capacity, regardless of how efficiently the apparatus may crush the cane, and in spite of the fact that the maximum yield of juice is obtained from the cane 30 acted upon, if said apparatus, due to inherent deficiencies therein, does not, while operating at its highest speed, grind a maximum tonnage of cane per day, the great expense attached to its acquisition and operation will render the use of the apparatus 35 unprofitable.

Briefly stated my improved cane crushing apparatus comprises a series of crushers or mills which act successively upon the cane, and the elements of each crusher are 40 so constructed and arranged that the cane crushed thereby is placed in a condition to be most effectively acted upon by the next succeeding crusher. Each of the rollers of the crushers or mills is preferably provided 45 with crushing ribs and the ribs on the rollers of the different crushers differ from each other, each crusher being provided with ribs adapted to most effectively act upon the cane delivered thereto, and also being adapted to 50 place the cane in such a condition that the next succeeding crusher will perform its function most effectively.

To obtain the maximum output from an apparatus of the type disclosed herein it is

necessary for each crusher and mill of said 55 apparatus to act upon the maximum amount of cane at all times while the apparatus is in operation, therefore if the maximum amount of cane is delivered to the second crusher of the apparatus, that crusher will 60 act upon the body of cane so delivered and as a consequence of the crushing action to which said body of cane is subjected it will be reduced in volume so that said body of cane will represent exactly the maximum 65 amount of cane which may pass through the next succeeding crusher, and this crusher will likewise reduce said body of cane to a size that represents the maximum amount of cane 70 which may pass through the first mill.

The problem therefore is to produce a cane crushing apparatus which is provided with means whereby a sufficient amount of cane may be drawn into the apparatus to cause 75 the individual crushers and mills of said apparatus to act upon a body of cane which represents the maximum capacity of each of said crushers or mills.

Prior to this invention the rollers of the 80 first crusher of cane crushing apparatus of the type disclosed herein have been of the same diameter as the rollers of the second crusher, and due to the fact that the body of cane which is introduced into said first crusher is in a very loose condition the passage of said body of cane through said first crusher will compress it so that said body of cane is far below the capacity of the second crusher, and because said body of cane is 85 below the capacity of the second crusher it 90 will be below the capacity of each succeeding crusher and mill through which it passes.

In the apparatus disclosed herein I employ a first crusher having rollers considerably larger in diameter than the rollers of 95 the second crusher and a second crusher having rolls which are larger in diameter than the rolls of the other crusher and of the mills, whereby the objections recited above are eliminated.

Fig. I is a diagrammatical view of a cane crushing apparatus embodying the features 100 of this invention.

Fig. II is a diagrammatical plan view of the cane crushing apparatus illustrated in 105 Fig. I, the crushing ribs which are shown on the rolls in Fig. I being omitted to simplify the view.

Fig. III is an enlarged fragmentary view showing the coarse crushing ribs on the rolls of the first crusher.

Fig. IV is a view similar to Fig. III, drawn to the same scale, and illustrating the cooperating crushing ribs on the rolls of the second crusher.

Fig. V is a fragmentary view drawn to the scale of Figs. III and IV, and showing the ribs on the rolls of the third crusher.

Fig. VI is a fragmentary view drawn to the scale of Figs. III, IV and V, and illustrating the ribs on the periphery of a roll of the first mill.

Fig. VII is a view similar to Fig. VI, and showing the ribs on the rolls of the second, third, fourth and fifth mills.

To illustrate the invention I have shown a succession of crushers, or mills, adapted to act upon the cane which travels through the apparatus, as indicated by arrows in Fig. I. The second crusher comprises a pair of crushing rolls A provided with peripheral ribs 1. These ribs are preferably V-shaped in cross-section, as shown in Fig. IV, and the ribs of one of the rolls A preferably overlap the ribs of the other roll, the ribs of each roll being extended into the corresponding peripheral grooves formed in the other roll. The third crusher comprises a pair of crushing rolls B smaller in diameter than the rolls of the second crusher and provided with ribs 2, which correspond approximately to the shape of the ribs of the first crusher. However, the ribs 2 of the third crusher are preferably of less pitch and smaller than the ribs of the second crusher. Furthermore the cooperating ribs of the third crusher are preferably located relatively close to each other, as shown in Fig. V. C designates the top roll of the first mill, D designates a lower roll, usually termed a "cane roll" and E designates a roll usually termed the "bagasse roll." Each of these rolls C, D and E is provided with peripheral crushing ribs 3 (Fig. VI) which are finer than the corresponding ribs of the third crusher. The second, third, fourth and fifth mills each consist of a top roll C', a cane roll D' and a bagasse roll E' and each of these rolls, which is the approximate diameter of the rolls of the third crusher and of the first mill, is provided with peripheral crushing ribs 4, shown in Fig. VII, said ribs being smaller and of less pitch than the ribs of the first mill.

The rotatable crushing rolls are provided with journals 5 adapted to be mounted in suitable bearings, but since such bearings are old and well known in the art, I do not deem it necessary to illustrate them in the drawings.

Arranged in advance of the second crusher is the first crusher F which is provided with a pair of crushing rolls G having peripheral

crushing ribs 6, said ribs, like the ribs on the rolls of the crushers already described, being V-shaped in cross section and cooperating with each other as do those ribs previously described. The rolls G of the first crusher F are of much greater diameter than the rolls of the other crushers, and the crushing ribs on said rolls of said first crusher are of greater pitch than the crushing ribs on said other rolls, consequently said rolls are able to draw into the apparatus a much larger body of cane at one time than they would if they were of the same diameter as the rolls of the other crushers. As already stated this feature of the apparatus is of the utmost importance due to the fact that the first crusher must draw into the apparatus a body of cane sufficient in volume to cause all of the subsequent crushers and mills to function to their extreme capacity.

The cane is introduced into the first crusher F in a very loose condition; in other words, the cane is not very closely packed. When this loose body of cane is introduced into the first crusher the large ribs 6 on the rolls of said crusher are adapted to mash and compress the cane whereby said body of cane is transformed into a comparatively compact mass which is passed on to the second crusher by said rolls of said first crusher. It is only by increasing the sizes of the rolls of the first crusher F that an amount of cane may be drawn into the apparatus which, when compressed by the first crusher, will be sufficient in volume to represent the maximum capacity of the second crusher. After the cane passes through the second crusher where it is acted upon by the finer ribs 1 which are adapted to split and shred the compressed cane and thus prepare it for the third crusher, it passes to said third crusher, and by increasing the diameter of the rolls of said second crusher, said second crusher accepts from the first crusher and passes on to the third crusher a body of cane which will represent the maximum amount which may pass through said third crusher. The body of cane then passes from said third crusher to the first, second, third, fourth and fifth mill in turn, the rolls on said mills and the ribs on said rolls being so arranged that they will effectively squeeze the juice from the mat of cane.

To provide means whereby the speeds of the various elements of my apparatus may be regulated I employ a separate power generating device 10 for actuating the first crusher, and a power generating device 11 which actuates the second and third crushers only. A power generating device 12 is connected to and actuates the first and second mills, and a power generating device 13 is connected to and actuates the third,

fourth and fifth mills. As will be seen by referring to Fig. II of the drawing, the various power generating devices are connected to the associated crushers and mills by means of suitable gearing but as said gearing is well known and forms no part of the present invention, I do not deem it necessary to describe same.

What I claim is:

- 10 1. In a cane-crushing apparatus, a primary crusher comprising a pair of crushing rolls, and a second crusher comprising a pair of crushing rolls arranged in advance of the primary crusher and adapted to receive the cane passing therefrom, the rolls of said primary crusher being of greater diameters than the rolls of said second crusher.
- 15 2. In a combined cane-crushing and juice-expressing apparatus, a primary crusher comprising a pair of crushing rolls,
- 20

a second crusher comprising a pair of crushing rolls arranged in advance of the primary crusher and adapted to receive the cane passing therefrom, and a juice-expressing mill arranged in advance of said second crusher, the rolls of said primary crusher being of greater diameters than the rolls of said second crusher, and the rolls of said second crusher being of greater diameters than the rolls of said juice-expressing mill.

25 3. A combined cane-crushing and juice-expressing apparatus comprising a plurality of sets of rolls whereby the cane is successively acted upon, the rolls of the first set being of greater diameters than the rolls of the other sets.

In testimony that I claim the foregoing I hereunto affix my signature.

HENRY HURTER.
